(57) **CLAIM**

The ornamental design for a “casting nozzle,” as shown and described.

DESCRIPTION

This application may also be deemed to be related to commonly owned U.S. Design patent application Ser. No. 29/306, 378 filed even date herewith entitled “Nozzle”, the entire content of which is expressly incorporated hereinto by reference.

FIG. 1 is front side elevational view of the casting nozzle which embodies our new and original design therefore, the rear side elevational view being a mirror image thereof;

FIG. 2 right side elevational view thereof, the left side elevational view being a mirror image thereof;

FIG. 3 is a top plan view thereof;

FIG. 4 is a bottom plan view thereof;

FIG. 5 is a cross-sectional longitudinal elevational view thereof as taken along line 5—5 in FIG. 1;

FIG. 6 is a cross-sectional latitudinal view thereof as taken along line 6—6 in FIG. 5; and,

FIG. 7 is an enlarged detail perspective view of the bottom encircled portion identified in FIG. 2 rotated 45 degrees.
